VLADIMIR K. ZWORYKIN, OF SWISSVALE, PENNSYLVANIA, ASSIGNOR TO WESTINGHOUSE ELECTRIC & MANUFACTURING COMPANY, A CORPORATION OF PENNSYLVANIA

WIRELESS PICTURE TRANSMISSION

Application filed May 10, 1929. Serial No. 361,900.

My invention relates to facsimile-transmitting-receiving systems and it has particular relation to systems of the type wherein the pictures or messages to be transmitted are on an opaque surface.

It has heretofore been proposed to mount a picture to be transmitted upon a cylinder and to reproduce, at the receiving station, the picture upon a sheet of light-sensitive material mounted upon a similar cylinder. Means for causing the two cylinders to rotate in synchronism and means for varying the light, at the receiving station, in accordance with the brightness of the several points in the picture being transmitted, have been also proposed. The proposals heretofore have, however, been limited to transmitting translucent pictures, such as photographic films, which can be viewed by transmitted light. Ordinary pictures, printed or typewritten documents and the like have necessarily, therefore, been photographed and the photographs developed before such pictures or documents could be utilized in a facsimile-transmitting system.

In my copending application, Serial No. 317,599, I have disclosed means whereby messages or pictures, upon opaque surfaces, may be expeditiously transmitted. I have also disclosed, in the said copending application, means for securing motional synchronism between the transmitting and the receiving apparatus. The present invention is an improvement over the invention disclosed in my copending application and has, as one of its objects, to provide a facsimile-transmitting-receiving system whereby a plurality of pictures or messages upon opaque surfaces may be transmitted without interrupting the process to recharge either the transmitting device with new matter or stopping the receiving apparatus to place additional light-sensitive material therein.

Another object of my invention is to provide a facsimile-transmitting-receiving system that shall be substantially unaffected by disturbances, such as static and the like.

In practicing my invention, I provide a carrying device, similar to a belt conveyor, which causes a continuous series of pictures

to be transmitted to pass through the path of a continuously-moving ray of light. The conveyor device is so disposed that, at the transmitting end, the picture is caused to assume a semi-cylindrical contour and is simultaneously advanced in the direction of the axis of the cylinder. The ray of light is caused to rotate around the axis of the cylinder at such angular velocity that each element of the picture is subjected thereto as it advances.

Reflected light from the picture or message is caused to fall upon a photo-electric cell, the output from which is utilized to modulate a radio transmitter, or a carrier-current transmitter, in the manner well known to those skilled in the art, or as disclosed in my copending application.

At the receiving end, a continuous strip of light-sensitive material is caused to assume a semi-cylindrical contour as it passes through the path traced by a moving ray of light from a glow tube or similar device. The ray of light from the glow tube is caused to rotate around the axis of the cylinder and thus traces a series of continuous lines on the light-sensitive strip, each line being separated from its predecessor by an amount proportional to the angular velocity of the ray and the speed of advance of the said strip. The intensity of the glow lamp is modulated by the incoming signal representative of the transmitted picture, in a manner well known to those skilled in the art.

In order that static and similar disturbances shall not adversely affect the transmission of the pictures, I may also so arrange the transmitting portion of the system that the picture or message is subjected to two or more rotating rays of light from a fixed source, the rays being so disposed with respect to the axis of rotation thereof that each element of the message or picture, in its advance, is subjected to the action of more than a single ray. The picture or message, therefore, is sent out by the transmitter substantially in duplicate and, at the receiving end, it is impressed upon a similar device by means of which two or more rotating rays from the receiving glow tube are caused to

fall upon each separate element of the light-sensitive strip during its advance.

The novel features that I consider characteristic of my invention are set forth with particularity in the appended claims. The invention itself, however, both as to its organization and its method of operation, together with additional objects and advantages thereof, will best be understood from the following description of a specific embodiment when read in connection with the accompanying drawings, in which

Figure 1 is a top plan view of a facsimile-transmitting device comprising a preferred embodiment of my invention.

Fig. 2 is a vertical sectional view of the apparatus, taken along a line corresponding to the line II—II of Fig. 1.

Fig. 3 is an end elevational view of the apparatus, looking toward the left.

Fig. 4 is an end elevational view of a portion of a receiving device.

Fig. 5 is a vertical sectional view, taken along a line corresponding to the line V—V of Fig. 4; and

Fig. 6 is a vertical sectional view of an alternative form of transmitting scanning device.

The apparatus illustrated in Figs. 1 and 2 comprises a housing 1 wherein is disposed a rotating scanning device hereinafter to be described in detail, a housing 2 adapted to contain a photo-electric cell 3 and a housing 4 adapted to contain a light source 5.

Means, comprising a plurality of endless cords 6, are provided for conveying a picture to be transmitted past the rotating scanning device, each of the said cords extending between a plurality of pulleys 7 and 8. The motive power for the cord-conveyor is supplied by a motor 10 connected, by appropriate gearing, to a vertical spindle 11 on which the pulleys 8 are mounted. Motive power for the scanning device is provided by a separate electric motor 12.

The construction of the scanning device will be more clearly seen from an inspection of Fig. 2. The said device comprises a hollow shaft 13 rotatably supported in appropriate bearings 14 and having a pinion 15 mounted thereon. The pinion is operatively connected to a worm wheel 16 mounted upon the shaft of the motor 12.

A plurality of lenses 17 are axially disposed within the hollow shaft 13 and serve to concentrate light from the source 5, contained within the housing 4, upon a plurality of prisms 18 that are affixed to the end of the hollow shaft farthest from the light source.

Each of the prisms 18 is so disposed with respect to a plurality of hollow arms 20 that extend at right angles to the axis of the shaft 13 that light from the source 5 is reflected from the said prisms through a plurality of lenses 21 carried by the hollow arms and

caused to be focused in a fine point on the inner surface of the cylinder defined by the picture to be transmitted, as such picture is constrained to assume such cylindrical form in its passage over a shielding device 22 under the control of the traveling cords.

As the cords constituting the conveyor pass the shielding device, they are held closely adjacent thereto by a plurality of small rollers 23, which are more clearly illustrated in Fig. 4.

The shielding device is provided with an opening (not shown) through which the light passes to fall upon the picture.

Each of the hollow extensions carrying the concentrating lenses 21 is provided with a coaxial parabolic mirror 24, the focus of which is coincident with the point in the plane of the paper at which the light from the source is focused. In addition, each of the said extensions passes through a mirror 25 disposed at an angle of 45° to the axis of the hollow shaft, which mirror gathers the light from the parabolic mirror and reflects it toward the photocell 3 mounted in the housing 2.

The housing for the scanning device is preferably provided with an eye-piece 26, the inner end of which carries a ground glass 27 of a similar screen, on which the light from the source may be focused for observation purposes during transmission.

In the operation of the apparatus shown in Figs. 1, 2 and 3, a plurality of separate typewritten messages, or a plurality of photographs or similar objects are fed, one at a time, between the cylindrical shield 22 and the traveling cord-conveyor, and are caused to slowly move in a direction parallel to the axis of the hollow shaft 13. The rate of travel of the cord-conveyor and the angular velocity of the hollow shaft are so adjusted that the message moves forward just sufficiently during a single rotation of the said shaft that the light from the source traces a series of parallel lines thereover. The reflected light, therefore, which is concentrated on the photocell by each parabolic mirror and the mirror 24 associated therewith, is representative, at each instant, of variations in the picture or message.

The manner in which the output current from the photocell is utilized to control a radio transmitter or a wired radio transmitter is familiar to those skilled in the art and forms no part of the present invention.

At the receiving station, a scanning device, similar to that used for transmitting, is utilized for the reception of the messages on a continuous strip of photo-sensitive material that is caused to advance by a cord-conveyor, or by any appropriate means, through the path traced by a rotating beam of light, which light varies in intensity according to the incoming signal.

The principal elements of the receiving device which differ structurally from those hereinbefore described in connection with the transmitter are shown in Fig. 5.

6 The means for providing a rotating beam of light comprises a driven shaft 30 to one end of which is affixed a hollow T-shape extension 31. A plurality of mirrors disposed at 45° to the axis of the shaft, or a plurality 10 of prisms 32, are mounted within the hollow extension. Light from a glow tube 33 is thrown upon the prisms, is reflected therefrom through a plurality of lenses 34, mounted in the arms of the extension 31, and 15 is concentrated as a fine point on the concave surface of the traveling photo-sensitive strip.

The glow tube, or other appropriate light source, is connected to the output terminals of an amplifier (not shown) and the light 20 therefrom is thus caused to vary in intensity proportionally to the incoming signal.

It will, accordingly, be apparent that, as the photo-sensitive strip is caused to assume a cylindrical shape by reason of the small 25 rollers 23 and the shielding device 22, the rotating T-shape extension carrying the lenses 34 traces a series of parallel lines across the said photo-sensitive surface. Inasmuch as the intensity of the light varies 30 proportionally to the incoming signal, the picture will be received in the form of a plurality of fine lines, each of which varies throughout its length in accordance with the illumination furnished by the glow tube.

35 An extremely important modification of my invention is illustrated in Fig. 6. This modification is, in many respects, the same as the embodiment shown in Figs. 1, 2 and 3, with the exception that the lens-carrying extension 31 is disposed angularly with respect to the axis of the rotating shaft. When the modified form of transmitter is utilized, the speed of travel of the picture and the angular velocity of the shaft are so correlated 40 that the lines of light traced by one lens system are duplicated by the lines of light traced by the other lens system. The picture is, therefore, actually sent in duplicate and, if proper means were provided at the receiving 45 station, two separate and distinct pictures could be received.

I prefer, however, to provide, at the said receiving station, a printing device somewhat similar to that shown in Fig. 5, but having 55 the arms of the T-shape extension staggered as shown in Fig. 6, whereby the photo-sensitive strip may be caused to advance at such speed with respect to the angular velocity of the shaft that the light-modulations, occasioned by the successive scanning of the 60 same picture or message element at the transmitter, are superimposed.

It will thus be apparent that, if static or other atmospheric disturbance causes the 65 obliteration of signals representative of one

scanning line at the transmitter, there is still the possibility that the duplicate scanning line will not be marred, and the picture, when received, will merely show minor variations in light and shadow, instead of having parts 70 thereof missing.

It also lies within the scope of my invention to provide more than two offset scanning lens systems at the transmitter and to similarly provide more than two offset scanning 75 lens systems at the receiver. The provision of three such systems at the transmitter and receiver, however, seems to give sufficient freedom from interference.

Although I have chosen certain specific 80 embodiments of my invention for purpose of illustration, it is not to be restricted thereto, inasmuch as many modifications thereof will be apparent to those skilled in the facsimile-transmission art. My invention, therefore, is 85 not to be limited, except in so far as is necessitated by the prior art or by the spirit of the appended claims.

I claim as my invention:

1. In a facsimile-transmitting-receiving 90 system, means for moving a light-receiving surface, and means for causing a plurality of angularly separated rays of light to so rotate in proximity of said moving surface as to trace a plurality of paths thereon transverse 95 to the direction of movement thereof, certain of said paths overlying each other.

2. In a facsimile-transmitting-receiving 100 system, means for moving a light-receiving surface, and means for causing a plurality of rays of light to so rotate in proximity to said moving surface as to trace a plurality of paths thereon, said light rays being angularly disposed with respect to their axes of rotation and so spaced apart from each other in 105 the direction of said axes, and the speed of movement of said surface being so correlated with the angular velocity of said rays, that each element of said surface is traced by more than one of said rays.

3. In combination, a source of light, means for deriving two diverging light rays from 110 said source, means for causing said light rays to rotate about a common axis, and means for causing a light-receiving surface to so move in a direction parallel to said common axis as to be repeatedly subjected to the action of said rays.

4. In combination, a source of light means for deriving from said source a plurality of light-rays that diverge at differing angles from a reference axis, means for causing said rays to rotate about said axis, and means for causing a light-receiving surface to so move in a direction parallel to said axis as to be 115 cyclically subjected to the action of said rays.

5. In a facsimile-transmitting-receiving 120 system, means for moving a light-receiving surface, means for causing a plurality of angularly separated rays of light to so rotate in 125

proximity to said moving surface as to trace a plurality of paths thereon transverse to the direction of movement thereof, and a plurality of rotating reflecting devices, one for each light-ray, for gathering light reflected from said surface and directing it along the axis of rotation of said rays.

6. The combination called for by claim 5 wherein the reflecting devices are each constituted by a parabolic mirror and a plane mirror.

In testimony whereof, I have hereunto subscribed my name this 4th day of May, 1929.

VLADIMIR K. ZWORYKIN.
